(57) CLAIM

The ornamental design for a wall-mounted bathroom shelf, as shown and described.

DESCRIPTION

2. Wall-mounted bathroom shelf

2.1 : Perspective

2.2 : Perspective

2.3 : Front

2.4 : Back

2.5 : Left

2.6 : Right

2.7 : Top

2.8 : Bottom

2.9 : Enlarged

The parts shown by means of broken lines in the reproductions are not part of the claimed design; fig. 2.9 is an enlarged view of a portion labeled "9" in fig. 2.1; the dash-dot-dash lines in fig. 2.1 and fig. 2.9, and the label "9" in fig. 2.1 are for the purpose of depicting the cut line of the enlarged view and form no part of the claimed design.

1 Claim, 9 Drawing Sheets
